UNITED STATES PATENT OFFICE.

AUGUST E. NEFF, OF CHICAGO, ILLINOIS.

DESIGN FOR BINDING.

44,071.

Specification for Design.

Patented May 20, 1913.

Application filed August 19, 1912. Serial No. 715,934. Term of patent 14 years.

To all whom it may concern:

Be it known that I, AUGUST E. NEFF, a citizen of the United States, residing at Chicago, in the county of Cook and State of Illinois, have invented a new, original, and ornamental Design for a Binding, of which the following is a specification, reference being had to the accompanying drawing, forming part thereof, and wherein the figure is a plan view of a portion of the binding, showing my new design.

I claim:

The ornamental design for a binding, as shown.

AUGUST E. NEFF.

Witnesses:

FRED G. KARDING,
HAROLD G. ROCKWELL.
